UNITED STATES PATENT OFFICE.

LOYAL MORTON BACH, OF SANTA MONICA, CALIFORNIA, ASSIGNOR TO BACH AIR-CRAFT COMPANY, INC., OF LOS ANGELES, CALIFORNIA, A CORPORATION OF DELAWARE.

DESIGN FOR A FUSELAGE FOR AEROPLANES.

Application filed August 7, 1928. Serial No. 27,736. Term of patent 14 years.

To all whom it may concern:

Be it known that I, LOYAL MORTON BACH, a citizen of the United States, residing at Santa Monica, in the county of Los Angeles and State of California, have invented a new, original, and ornamental Design for a Fuselage for Aeroplanes, of which the following is a specification, reference being had to the accompanying drawing, forming a part thereof.

Figure 1 is a front elevation of a fuselage for aeroplanes showing my new design.

Fig. 2 is a side elevation of the same.

Fig. 3 is a top plan view of the same.

I claim:

The ornamental design for a fuselage for aeroplanes as shown.

Signed at Los Angeles, in the County of Los Angeles, and State of California, this 21st day of July, 1928.

LOYAL MORTON BACH.
